WELL-DRILLING BIT

William Carleton Starkey, Indianapolis, Ind., assignor of one-half to Arthur E. Krick

Application June 27, 1936, Serial No. 87,601

5 Claims. (Cl. 255—61)

My invention relates to well-drilling heads or bits and has for its object the production of a bit which will drill more rapidly in substantially all forms of material and which will be more durable than other bits of which I am aware. A further object of my invention is to produce a bit which will embody no relatively moving parts and which will therefore be free from bearing surfaces subject to excessive wear.

10 In carrying out my invention, I form the bit as a series of end milling cutters of gradually increasing diameter from the lower end of the bit to the top, these cutters preferably being formed by independent rings held in place on a suitable core 15 which is attached to the lower end of the drill pipe. The outer cylindrical surface and the lower face of each of these rings are provided with an annular series of cutting teeth; and the lowermost ring has associated with it a central insert adapted to break up the core left by the teeth of that ring. The core upon which the several rings are mounted is hollow and is supplied through the drill pipe with water under relatively high pressure, such water preferably discharging from the 20 interior of the core through ports at least one of which is located at the lower end of the bit and others of which are located intermediate the height of the bit.

25 The accompanying drawing illustrates my invention: Fig. 1 is a vertical axial section through a complete drill bit embodying my invention; Fig. 2 is a bottom plan view of the lowermost cutter; and Fig. 3 is a side elevation of such lowermost cutter.

30 As shown in the drawing the body 10 of the bit consists of a single piece of metal, conveniently a casting, and has at its upper end an axially extending boss 11 provided exteriorly with screw threads for engagement with a coupling 12 by 35 which the head is connected to the lower end of the drill pipe 13. Below the boss 11, the head has an annular flange 15 and below this flange a series of steps of gradually decreasing diameter toward the bottom of the body. As shown, there 40 are five of such steps, 16, 17, 18, 19, and 20, but the number may vary.

45 Upon each of the steps 16, 17, 18, 19, and 20 there is mounted an annular cutting element, such cutting elements being designated in the drawing by the reference numerals 21, 22, 23, 24, and 25. A sixth annular cutting element 26 is disposed at the extreme bottom of the body 10 and has an upwardly extending boss 27 provided exteriorly with screw threads by means of which it is retained in place on the body. Each of the

5 cutting elements has an axial thickness a few thousandths of an inch greater than the effective width of its associated step and an external diameter greater than the diameter of the step next above it, so that by the action of the screw threads 10 on the boss 27 the lowermost cutting element 26 can be rotated to clamp all the cutting elements 15 in place.

15 Each of the cutting elements is provided with an annular series of cutting teeth extending vertically across the cylindrical face of the cutting element and inwardly along the bottom face thereof at least to a point within the circumference of the cutting element next below. The base diameter of the upper cutting element 21 is preferably not less than the diameter of the flange 15, so that the flange 15 will not interfere with the movement of the cuttings passing upwardly through the spaces between the teeth of that cutting element.

20 Rotation of each cutting element on the body 10 is prevented by any suitable means, the means shown comprising one or more keys 30 associated with each cutting element.

25 To break up the core which would otherwise be left by the lowermost of the annular cutting elements 26, I mount in such cutting element an insert 32 having a pair of cutting edges which slope outwardly and upwardly from its center and have their upper ends above the plane of 30 the cutting edges of the teeth on the lower cutting element 26. Conveniently, the insert 32 is of flat stock the edges of which are received in diametrically opposite key-ways in the bore 33 of the cutter 26. To prevent the insert from dropping out of its seat, its upper end may be formed with two outwardly projecting ears 34 overlying the upper end of the boss 27, as is clear from Fig. 1.

35 The body 10 of the head is hollow and receives 40 water under pressure through the drill pipe 13. At least a part of this water is expelled downwardly between the sides of the insert 32 and the wall of the bore 33, which bore desirably tapers toward its lower end in order to produce an effective nozzle. The water discharged at the lower 45 end of the lowermost cutting element 26 is forced first outwardly and then upwardly through the spaces between the teeth of that element, thence into the spaces between the teeth of the next element 25, and so on upwardly through the spaces between the teeth of the successively higher cutting elements. It has been found desirable to proportion the number of teeth on each cutting element to the diameter thereof so that the cir- 50 55

cumferential pitch of the teeth of all cutting elements will be approximately the same. As a result of this, all the teeth of one cutting element can not be in alinement with all the teeth of the cutting elements above and below it; and to prevent interference with the free upward flow of water and the cuttings suspended therein, I find it desirable, at least in the case of the larger cutting elements below the uppermost cutting element 21, to provide an annular groove 36 along the outer upper edge of each cutting element. These various grooves 36 provide for any circumferential movement of water or cuttings that may be necessary to permit them to enter into the spaces between the teeth of the next higher cutting element.

I find in practice that it is difficult if not impossible to secure an adequate flow of water through the relatively small bore 33 in the lowermost cutter 26, and I therefore provide for the emergence of water from the interior of the body 10 at a level above the lower end of the bit. To this end one of the steps on the body 10, shown in the drawing as the step 19, has a width materially greater than the thickness of its associated cutter 24, and above the cutter 24 the annular wall of the body 10 is drilled radially for the reception of nozzle-bushings 38. These bushings project outwardly beyond the annular wall of the head-body into a ring 40 which is mounted on the step 19 above the cutter 24. The lower end of the ring 40 is received in a counterbore in a second ring 41 which rests upon the cutter 24 and which is clamped between the ring 40 and the cutter 24 by the clamping action of the screw threads on the boss 27 of the lowermost cutter 26. The ring 40 projects radially outwardly only a slight distance, if any, beyond the outer ends of the bushings 38, but the second ring 41 is of materially larger external diameter and has its upper face dished, to provide an outwardly and upwardly sloping surface 42. Water emerging outwardly through the nozzles 38 impinges upon the surface 42 and is deflected upwardly against the lower surface of the cutting element 23. By imparting an upward component to the water discharged through the nozzles 38, I am enabled to prevent such water from interfering with upward flow of the water which is discharged through the bore 33 of the lowermost cutting element 26.

When a drill head as described is in use, the teeth on the lower surfaces of the various cutting elements cut the rock or other material through which the head is passing into relatively small particles which are carried upwardly by the streams of water emerging from the bore 33 in the lowermost cutter and from the nozzles 38. The action of the cutting teeth of each cutting element is such that they not only remove the material which they directly engage but also fracture the material for a short distance beyond the periphery of that cutting element. The fractures thus produced aid materially in the action of the end cutting teeth of the cutting element next above.

It is to be noted that the spaces between the teeth on the outer and bottom faces of the cutting elements form the sole passages for the water which is discharged from the interior of the body. As a result, such water is compelled to flow in substantial contact with all the cutting edges and tends to carry away immediately all particles which those cutting edges dislodge. Further, all recesses on the outer surface of the

head are water passages, and there are no pockets in which the cuttings can collect. Since the aggregate cross-sectional area of the water passages, even in the case of the largest cutting element, is materially less than that of the annular space above the flange 15, the water passing the cutting edges is maintained under high pressure which is effective to dislodge any rock fragments or other material that would otherwise tend to collect between the teeth.

If all the end cutting teeth of each cutter were in the same plane, the total downwardly directed thrust on the head would be divided equally between all the teeth. To prevent the necessity for an excessive downwardly directed thrust when the head is cutting through hard material, therefore, I prefer to arrange the end teeth of each cutting element so that some of them extend a short distance downwardly beyond the remainder. This is indicated in exaggerated form in Fig. 3, where the lowermost cutting element 26 is shown as having nine teeth three of which, equally spaced, project downwardly beyond the other six. Preferably, these teeth are made as hard as possible, as by facing them with tungsten carbide or some other suitable substance of a type which stands up well under an abrasive cutting action. The proportionate number of cutting teeth on each cutting element which thus project beyond the others may vary, but I have found it convenient to use the proportions indicated in Figs. 2 and 3 in the case of the cutter 26—namely, one long tooth for each two short teeth.

The distance by which the long teeth project beyond the short teeth should be some distance intermediate between the depth of cut taken by each tooth in hard material and the depth of cut taken in soft material. I find in practice that while in excessively hard rock each tooth may feed only a few thousandths of an inch each tooth, in soft material, may feed as much as $\frac{1}{8}$ of an inch, and I therefore prefer to have the long teeth project approximately 0.010 inch below the short teeth. In excessively hard rock, the long teeth will do all the cutting, although the shorter teeth may aid in breaking up chips which the longer teeth dislodge. In soft material, all the teeth may cut, although the depth of the cut of the longer teeth will be slightly greater than that of the shorter teeth.

I claim as my invention:

1. In a drill head, a cutting element screw-threadedly mounted at the lower end of said head, said cutting element having an annular series of end cutting teeth and an axial bore extending through it and constituting a fluid passage, and a removable member of flat stock disposed in said passage and dividing it longitudinally, said bore being provided with key-ways receiving the edges of said member, said member having at its lower end a generally diametrically extending cutting edge located at least in part above the cutting edges of the teeth on said cutting element.

2. In a drill head, a cutting element screw-threadedly mounted at the lower end of said head, said cutting element having an annular series of end cutting teeth and an axial bore extending through it and constituting a fluid passage, and a removable member of flat stock disposed in said passage and dividing it longitudinally, said bore being provided with key-ways receiving the edges of said member, said member

having at its lower end a generally diametrically extending cutting edge.

3. In a drill head, a body having an annular flange and below such flange a series of annular steps decreasing in diameter toward the lower end of the body, an annular element mounted on each of said steps, each of such elements having an external diameter greater than the internal diameter of the element next above it, each of 10 said elements projecting downwardly below the end of the associated step to engage the element next below, some of said elements being provided respectively with annular series of cutting teeth, and a clamping member having an external diameter greater than the internal diameter of the 15 annular element immediately above it and also having an upwardly projecting axial boss screw-threadedly received in said body at the lower end thereof, said clamping member having an annular 20 series of cutting teeth.

4. In a drill head, a body having an annular flange and below such flange a series of annular steps decreasing in diameter toward the lower end of the body, an annular element mounted on each of said steps, each of such elements having an external diameter greater than the internal diameter of the element next above it, each of 25

said elements projecting downwardly below the end of the associated step to engage the element next below, some of said elements being provided respectively with an annular series of cutting teeth, and a clamping member having an external diameter greater than the internal diameter of the 5 annular element immediately above it and also having an upwardly projecting axial boss screw-threadedly received in said body at the lower end thereof.

5. A drill head, comprising a plurality of rigidly connected cutting elements, provided respectively with co-axial annular series of end cutting teeth, said elements being of increasing diameter from the bottom of the head toward the top, and means associated with the lowermost cutting element for breaking up the core left by its annular series of end cutting teeth, said head being hollow and provided with a water-discharge opening at the bottom of the head and with one or more 20 additional water-discharge openings at a point intermediate the lowermost and uppermost cutting elements, said head also having means for deflecting upwardly water discharged from said additional openings. 25
